UNITED STATES PATENT OFFICE.

EDWARD PERRIN, OF KIDDERMINSTER, ENGLAND, ASSIGNOR TO JOSEPH WILD & CO., OF NEW YORK, N. Y.

DESIGN FOR CARPET.

Specification forming part of Design No. 6,232, dated October 29, 1872.

To all whom it may concern:

Be it known that I, EDWARD PERRIN, of Kidderminster, in the county of Worcester, England, have invented a new and original Design for a Carpet, of which the following is a specification:

The accompanying photograph fully illustrates my new design.

This invention relates to a new design for carpets or similar fabrics, and is composed of groups of large squares arranged about smaller squares, and with intervening narrow oblong

spaces. The large squares, of which four are around each small square, contain ornamental rosettes. The narrow spaces are also ornamented by oval rosettes, as shown.

I claim as my invention—

The design for a carpet, as shown.

EDWD. PERRIN.
